UNITED STATES PATENT OFFICE.

CLARENCE SAUNDERS, OF MEMPHIS, TENNESSEE, ASSIGNOR TO PIGGLY WIGGLY CORPORATION OF MEMPHIS, TENNESSEE, A CORPORATION OF DELAWARE.

SELF-SERVING STORE.

Application filed November 17, 1917. Serial No. 202,466.

To all whom it may concern:

Be it known that I, CLARENCE SAUNDERS, a citizen of the United States, residing at Memphis, Shelby County, and State of Tennessee, have invented and discovered certain new and useful Improvements in Self-Serving Stores, of which the following is a specification.

In the installation of self-serving stores of 10 the character forming the subject matter of my Letters Patent No. 1,242,872, and in the development and practice of said invention, I have devised many modifications in the structure of the apparatus shown in said 15 patent; and, although I regard the construction as therein shown and described to be preferred for ordinary uses, yet in some cases, certain of these other modifications may be found of advantage, and desirable. 20 My present application is for the purpose of disclosing certain of these modifications and secure to myself the protection of a patent for the invention so disclosed.

In the accompanying drawing, Figure 1 25 illustrates a plan view of a set of cases as they would stand in a store in accordance with my said invention, Figure 2 a detail side elevation as seen when looking in the direction of the arrows when looking from 30 the dotted line 2—2 in Figure 1, and Figure 3, a modified form.

In the drawings the portions marked A represent the cabinets or merchandise holding cases; B a turnstile at the entrance; C 35 railings or partitions; D the turnstile at the exit; E a checking and settlement stand, and F a basket-rack.

The cabinets or cases are to be arranged in a storeroom with a lobby in front, as in 40 the above mentioned Letters Patent, and consisting of shelving divided appropriately into compartments for containing goods of various assortments, as may be desired. The turnstile B is of any approved type mounted 45 at the entrance and designed to practically span the space between the adjacent rows of shelving A. These cabinets are shown as comprising two side elements and a connecting rear element, all having merchandise holding shelves or compartments, but the particular form is not material so long 50 as it enables aisles to be formed adjacent the merchandise display therein.

The railing C is mounted midway between 55 the adjacent parallel rows of shelving A,

and extends from a point near the front of the cabinet to a point near the rear. The front is closed by one of the arms of the turnstile while the rear end is left open to form a passage-way around the rear end 60 of said partition. This cabinet A, the turnstile B and the partition C, associated with the checking and settlement stand may in itself constitute a self-serving booth, capable of use in department stores, or other 65 places as found desirable. I have shown this cabinet as duplicated, the two being arranged side by side so that the customer upon entering, passes down the aisle 10, up the aisle 11, down the aisle 12, up the aisle 70 13, and out by the exit turnstile D past the checking and settlement stand E. Before entering, the customer takes a basket from the basket rack F.

A railing 14 extends from the partition C 75 to a point on the frame of the basket rack F, furnishing a top support for the turnstile post 15, and serving as a means for preventing the customers from passing out by the turnstile B as they come out of the aisle 80 11. In cases where a single cabinet A is used, as a booth for dispensing merchandise by the self-serving system, this railing would be dispensed with so that the customer might pass in on one side of the turnstile 85 and out by the other side.

It will be understood, of course, that as many of the cabinets may be arranged side by side as desired, the settlement counter or stand E being adjacent to the ultimate exit 90 turnstile.

In Figure 3 I have shown a modified form in which, in lieu of the partition or railing C, I have shown a case H with shelving on both sides and positioned midway between the two turnstiles. This arrangement gives more shelving space and may be utilized where the size of the store, or the place where the cabinet or booth is used, makes it more desirable.

The method of operation is identical with that disclosed in my above mentioned Letters Patent, the customer selecting his purchases from the goods displayed in the cabinets as he passes down one aisle and up the 105 other, paying for the same at the settlement stand at the exit, and passing out of the store.

In the modified form of cabinet, as shown in Figure 3, I have indicated the shelving by 110

the reference letter G and the central case by the reference letter H.

It will be noted that the rear end of these booths, or cabinets, are shown as closed, but it will be understood of course, that doors may be formed in the rear, (indicated by dotted lines) communicating with the stock room, as shown in my patent above referred to, when conditions will permit. By this arrangement the customers passing through the store, or booth, may be observed at all times from the settlement stand.

Having thus fully described my said invention, what I claim as new and desire to secure by Letters Patent is:

1. An apparatus for the vending of merchandise comprising a cabinet having parallel rows of shelving and shelving across the rear, a partition extending from the front nearly to the rear, and a turnstile adapted to close said front and positioned with two of its arms normally in line with the partition in said cabinet, and the other two arms extending across the front of said cabinet, substantially as set forth.

2. In a self-serving store, a U-shaped display cabinet comprising side and rear display sections, a partition parallel to the side sections and extending nearly to the rear section, thereby providing a circuitous path for customers, with display devices at one side only, and a turnstile at the entrance to the unit, said turnstile having two arms barring the entrance and outlet respectively and a third forming a continuation of the partition, substantially as set forth.

3. In a self-serving store, a plurality of display units arranged in rows facing each other, partitions of lesser length extending between said rows, thereby forming a circuitous path for customers with display devices adjoining the path at one side only, turnstiles at the exit and entrance to the path, each turnstile having two arms closing the space between two adjacent display units, and a third arm forming a continuation of an adjacent partition, substantially as set forth.

4. In a self-serving store, a plurality of display units arranged in rows facing each other, partitions of lesser length extending between said rows, thereby forming a circuitous path for customers, with display devices adjoining the path at one side only, turnstiles at the exit and entrance to the path, each turnstile having two arms closing the space between two adjacent display units, a third arm forming a continuation of an adjacent partition, and a checking and settlement stand forming with the fourth arm of the turnstiles a connecting part of said path, substantially as set forth.

5. An apparatus for vending merchandise comprising a series of merchandise containers arranged parallel with each other

and a distance apart, a rail between said cabinets for dividing the space into aisles and extending near to each end thereof, a turnstile arranged to close the entrance end and the exit end of the aisle thus formed, the turnstile being arranged so that one arm thereof will close the space between the end of said rail and the turnstile, and its two arms at right angles therewith will close the entrance to the space between the cabinets, and a checking and settlement stand adjacent to said turnstile, substantially as set forth.

6. In a self-serving store having a lobby and a sales section, a series of rows of merchandise containers and interposed partitions providing a circuitous pathway for customers, a checking and settlement station in the lobby, a row of merchandise containers spaced from one side of the checking and settlement station by a transverse portion of said circuitous pathway, turnstiles at the entrance and exit of the sales section having arms defining the ends of said transverse portion, said arms being aligned with certain of said partitions and with opposite sides of the checking and settlement station, one of said sides facing toward the exit passage from the sales section to the store door and the other having thereon a basket rack adjacent the entrance passage from said door to the sales section, substantially as set forth.

7. In a self-serving store having a lobby and a sales section, store furniture arranged to form a U-shaped cabinet for the display of goods, a partition parallel to the sides of the cabinet and spaced from an end thereof to provide aisles forming a circuitous passageway for customers, a checking and settlement station at the lobby end facing toward said aisles, and a basket rack adjacent the checking and settlement station extending along the passage leading from the entrance to said store into the entrance end of said circuitous passageway, said rack being located between the checking and settlement station and said passage, substantially as set forth.

8. In a self-serving store having a lobby and a sales section, store furniture arranged to form a U-shaped cabinet, a partition parallel to the sides of the cabinet and spaced from an end thereof to provide aisles forming a circuitous passageway for customers, a checking and settlement station at the lobby end facing toward said aisles, and a basket rack forming a part of the enclosure of the checking and settlement station and extending along the passage leading from the entrance to the store into said passageway, substantially as set forth.

9. In a self-serving store having a lobby and a sales section, store furniture arranged to form a U-shaped cabinet for the display

of goods, a partition comprising a case with shelving on both sides parallel to the sides of the cabinet and spaced from an end thereof to provide aisles forming a circuitous 5 passageway for customers, a checking and settlement station at the lobby end facing toward said aisles, and a basket rack adjacent the checking and settlement station extending along the passage leading from 10 the entrance to said store into the entrance end of said circuitous passageway, said rack

being located between the checking and settlement station and said passage, substantially as set forth.

In witness whereof, I have hereunto set 15 my hand and seal at Memphis, Tennessee, this 15th day of November, A. D. nineteen hundred and seventeen.

CLARENCE SAUNDERS. [L. s.]
